United States Patent Office.

ALEXANDER F. B. ROCKE, AND WILLIAM H. MCLEOD, OF JERSEY CITY, NEW JERSEY.

Letters Patent No. 94,652, dated September 7, 1869.

IMPROVED RAILWAY-SIGNAL.

The Schedule referred to in these Letters Patent and making part of the same.

To all whom it may concern:

Be it known that we, ALEXANDER F. B. ROCKE and WILLIAM H. MCLEOD, both of Jersey City, county of Hudson, and State of New Jersey, have invented a new and useful Improvement in Railroad-Signals for Locomotives; and do hereby declare that the following is a general description thereof, reference being had to the accompanying drawings, making part of this specification, of which—

Figure 1 is a plan or top view;

Figure 2, a side elevation; and

Figures 3 and 4, end elevations of our invention.

This invention relates to a novel device for displaying preconcerted signals, for apprising engine-drivers on other trains, and all other persons concerned, of the passage or progress of the train which operates the signals, when the locomotive and train are entering or leaving a tunnel, approaching a drawbridge, passing on a curve, or at any other desired point on the road, where danger may be apprehended, and avoided by means of signals; and

It consists of two or more semi-elliptical springs, placed beside the rail, and at any desired distance apart, and in such manner that the wheels of the locomotive in travelling on the rail shall bear on the first elliptical spring, which is connected with the signal by means of levers, and will display the signal from a post, warning all concerned that the track is occupied by the locomotive and train of cars, and will, in like manner, by passing over a similar spring and mechanism, placed at a remote distance from the other, drop the signal, intimating thereby that the locomotive and train had passed; and

It further consists in a portable bulk-head, attached at any desired point on the road to a lever, to a post, or to one of the rails, in such manner that, by means of an arm, connected with the steam-whistle of the engine, said arm will strike the bulk-head, and sound an alarm on approaching danger.

In the accompanying drawings—

A A indicate the railroad-rails;

B B, &c., the ties or sleepers; and

C C, elongated ties, which support the mechanism for operating the signals.

This mechanism consists, in the first place, of two semi-elliptical springs D E, which may be placed a

mile, more or less, apart, each spring forming an arch, the ends of which play loose in staples F F, attached to the sleepers.

These arched springs are placed in close proximity to one of the rails, and rise above the rail, so that the wheels of the locomotive, while travelling on the rail, will press downward, in the first place, the semi-elliptical spring E, thereby bearing down the lever R, and raising the vertical connecting-rod L, and crank or arm M, so as to throw out and display the signal O, which is held thus by means of the weighted balance-arm K, that holds the horizontal rod I into a notch, k, in the weighted vertical arm Q, until the locomotive reaches the other elliptic spring D, whereby the lever G is vibrated, and consequently the rod I is withdrawn from the notch k, thus allowing the signal O to fall and withdraw from view.

Furthermore, the lever R carries a vertical post, S, to act as a stop, against which a rod, connected with the whistle of the locomotive, comes in contact, and by means of which an alarm is sounded on approaching danger.

For the stop S, an arm T, attached to the post P, as shown in red lines, may be substituted, or a portable stop, as shown in red lines, at W, attached to the rail by clamping-screws.

In this latter case, the stop may be placed inside of the rails, and the rod V, connected with the steam-whistle, brought down between the wheels of the locomotive and near to the fire-box, so as to strike the portable stop W, as a modification of our invention, if preferred.

Having described our invention,

What we claim, and desire to secure by Letters Patent, is—

The semi-elliptical springs D E, levers G R, rods I L, arms K R, and stop S, all arranged and operating substantially as and for the purposes described and set forth.

In testimony whereof, we have hereunto set our signatures, this 11th day of May, A. D. 1869.

ALEXANDER F. B. ROCKE.

WILLIAM H. MCLEOD.
